[57] CLAIM

The ornamental design for a combined removable vehicular mud flap unit and hitch adapter, as shown and described.

DESCRIPTION

FIG. 1 is a perspective view of a combined removable vehicular mud flap unit and hitch adapter showing my new design, it being understood the broken lines are for illustrative purposes only and form no part of the claimed design;

FIG. 2 is a top plan view thereof;

FIG. 3 is a front elevation view thereof;

FIG. 4 is a left side elevation view thereof;

FIG. 5 is a right side elevation view thereof;

FIG. 6 is a bottom plan view thereof; and,

FIG. 7 is a rear elevation view thereof.

FIG. 1

FIG. 2

FIG. 3

FIG. 4

FIG. 5

FIG. 6

FIG. 7
